UNITED STATES PATENT OFFICE.

JAMES MILES AKERS, OF GAYS, ILLINOIS, ASSIGNOR TO MATTOON GRAIN CONVEYOR CO., OF MATTOON, ILLINOIS.

PNEUMATIC GRAIN-CONVEYER.

No. 824,056.

Specification of Letters Patent.

Patented June 19, 1906.

Application filed May 4, 1905. Serial No. 258,846.

To all whom it may concern:

Be it known that I, JAMES MILES AKERS, a citizen of the United States, residing at Gays, in the county of Moultrie and State of Illinois, have invented a new and useful Pneumatic Grain-Conveyer, of which the following is a specification.

This invention relates to pneumatic grain-conveyers, and especially to devices of this class whereby grain, shelled corn, and the like may be loaded into railroad-cars for transportation with the manual labor involved in throwing the material toward the ends of such cars.

The invention has for its object to present an apparatus of this character which shall possess superior advantages in point of simplicity, durability, and general efficiency; and with these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of embodiment of the invention, it being, however, understood that no limitation is necessarily made to the precise structural details therein exhibited, but that the right is reserved to any changes, alterations, and modifications to which recourse may be had within the scope of the invention and without departing from the spirit or sacrificing the efficiency of the same.

In said drawings, Figure 1 is a sectional elevation of a pneumatic grain-conveying apparatus constructed in accordance with the principle of the invention. Fig. 2 is a top plan view of the same.

Corresponding parts in both figures are indicated throughout by similar characters of reference.

The improved device includes a blower the casing of which, 1, is provided in the usual manner with bearings for a shaft 2, upon which is mounted a hub 3, having radiating arms 4, carrying fan-blades 5 of ordinary construction. The blower takes air through the eyes in the sides of the casing and discharges through an outlet 6.

Supported upon the part of the casing which constitutes the outlet portion 6 is an

auxiliary casing 7, of approximate cylindrical shape and provided in the ends thereof with bearings for a shaft 8, carrying a paddle-wheel 9, the wings or paddles of which, 10 10, are extended into approximate contact with the walls of the casing, so that grain or material that is to be operated upon may not pass between said wings and the walls of the casing. The latter is provided in one side thereof with an inlet 11, connected with a conducting-tube 12. The lower part of the casing 7 communicates with the outlet 6 of the blower-casing through an opening 13.

Supported for oscillation in the sides of the inlet member 11 is a rock-shaft 14, carrying a valve or damper 15 and an adjusting-lever 16, which latter may be placed in engagement with notches in a quadrant 17 for the purpose of retaining said lever and the damper 15 at any desired adjustment. It will be observed that by properly adjusting the damper the inlet-opening, through which material may be admitted into the casing 7, may be regulated to govern the quantity of material that shall be permitted to enter into said casing 7.

Hingedly connected with the discharge member 6 is a chute 18, terminating in a Y 19, the branches of which extend in opposite directions, as clearly seen in Fig. 2 of the drawings.

The fan may be driven by means of a belt 20 of any suitable source of power. Motion may be transmitted to the paddle-wheel 9 from the fan-shaft by means of a crossed belt 21, the speed being governed by the relative sizes of the pulleys or band-wheels.

When the device is in operation, the forked end of the discharge-chute may be inserted through the door of a railroad-car, as indicated at 22, the fan being driven at the desired speed and rotary motion being transmitted to the paddle-wheel. By properly adjusting the damper 15, which may also constitute a closure, material may be permitted to flow through the inlet 11 into the casing 7, from which it is discharged by the paddle-wheel 9 through the opening 13 into the discharge-opening of the blower, from which it is carried by the air-current through the chute 18 and the branches of the Y 19 into the car, said material being simultaneously deposited in opposite ends of the car, which may thus be speedily loaded without

necessity for manually shifting the contents, as is invariably necessary when a car is loaded merely by gravity, and thus dispensing with much labor of a very unpleasant nature.

5 It will be observed that the valve or damper 15 may be adjusted and secured in various positions so as to regulate and positively control the quantity of material permitted to pass through the spout or chute 12 into the 10 feeder-casing and that the passage of material through said spout may be cut off entirely when desired. This is obviously important in order not to overfeed the device or supply it with material beyond the capacity of the 15 fan. Another important feature of the invention resides in the fact that the paddle-wheel within the feeder-casing virtually constitutes a closure, the wings or paddles being extended to the walls of the casing to prevent 20 passage of material between said walls and wings or paddles. It follows that when the device is in operation the material passing into the feeder-casing will be forcibly propelled by the paddle-wheel in a forward direction 25 through the opening 13 into the chute 6 and into the air-current which is being forced therethrough by the action of the fan, no portion of the material being permitted to pass into the chute 6 by gravity only. The chute 30 when not in use may be readily folded back upon the casing of the apparatus, so as to be

out of the way, owing to the presence of the hinge-joint 23, provided for this purpose.

Having thus described the invention, what is claimed is—

1. In a pneumatic conveyer, a fan-casing having a discharge-spout, an auxiliary casing constituting a feeder-casing located above and communicating with the discharge-spout, a feed-spout communicating with the 40 feeder-casing, and a paddle-wheel supported for rotation within, and having wings or paddles extending to the walls of said feeder-casing to prevent the passage of material between said wings and the walls of the casing. 45

2. In a pneumatic conveyer, a fan-casing having a discharge-spout, an auxiliary casing constituting a feeder-casing located adjacent to and communicating with a discharge-spout, a paddle-wheel supported for rotation 50 within the auxiliary casing, a feed-spout connected with the latter, a valve or damper in the feed-spout, and means for operating said valve or damper and for securing it at various adjustments.

In testimony that I claim the foregoing as my own I have hereto affixed my signature in the presence of two witnesses.

JAMES MILES AKERS.
